UNITED STATES PATENT OFFICE.

LAURA M. FLEMING, OF TONOPAH, NEVADA.

CRATE.

1,242,430.

Specification of Letters Patent.

Patented Oct. 9, 1917.

Application filed December 12, 1916. Serial No. 136,489.

To all whom it may concern:

Be it known that I, LAURA M. FLEMING, a citizen of the United States, residing at Tonopah, in the county of Nye and State 5 of Nevada, have invented certain new and useful Improvements in Crates, of which the following is a specification.

This invention relates to crates, and more particularly to a crate of the folding type.

10 One of the main objects of the invention is to provide a crate of the character stated of simple construction and operation which may be produced at relatively low cost. A further object is to provide a crate in which 15 all of the parts of the crate are permanently connected thus eliminating all danger of losing any of these parts. A still further object is to provide a crate which can be quickly and easily folded so as to occupy 20 but very little space, and can be as quickly and easily unfolded for use. Further objects will appear from the detailed description.

In the drawings:

25 Figure 1 is a top plan view of a crate constructed in accordance with my invention; Fig. 2 is a side view of the same;

Fig. 3 is an end view;

30 Fig. 4 is an enlarged vertical transverse sectional view taken substantially at the longitudinal center of the crate;

Fig. 5 is a longitudinal vertical sectional view taken at the transverse center of the crate.

35 Broadly stated, my crate comprises a bottom, and top and side frames pivotally secured thereto and to each other so as to fold laterally and downwardly upon the bottom, in combination with partition members hing- 40 edly secured to the bottom so as to fold downward on to the same.

The bottom of the crate is formed from the sheet metal plate 1 at each end of which is secured a rectangular reinforcing strip 2.

45 A transversely extending strip 3 is secured to the under face of plate 1 at the longitudinal center thereof. This strip is cut at each end and turned upward at right angles to provide an integral vertically extending

50 tab 3^a at each side of the crate. Each of these tabs projects through an inwardly extending slot cut through the plate 1. Each side frame of the crate is composed of the corner rectangular uprights 4, the intermediate rectangular upright 5, and the upper and lower strips 6 and 7, respectively, which

are riveted to the uprights 4 and 5. Each of the end uprights 4 has its transversely extending arm 4^a pivotally secured to the vertical arm 2^a of the rectangular reinforcing strip 2, as at 2^b. The transversely extending arm 5^a of the intermediate standard 5 is similarly secured to the tab 3^a as at 9. By this means each side of the crate is pivotally secured to the bottom of the crate so 60 as to be foldable inwardly and downwardly into parallelism with, and closely adjacent to, the bottom. By having the transversely extending arms 4^a of the corner uprights 4 positioned outside of the vertical arms 2^a of 70 the reinforcing strips 2, these members will fit down snugly about the reinforcing strip, as indicated by the broken line position of the parts in Fig. 4 of the drawing.

The top of the crate is composed of the 75 end transversely extending rectangular bars 10, the intermediate rectangular bar 11, the longitudinally extending reinforcing strips 12 riveted to these transverse bars, and the transverse reinforcing strips 13 riveted to 80 the strips 12. Each of the bars 12 is positioned with its vertical arm 12^a outside of the transversely extending arm 4^a of the corner upright 4 and this arm 12^a is pivotally secured to the arm 4^a of the upright 85 4, as at 14. The ends of the vertical arms 11^a of the intermediate bar 11 are pivotally secured to the transversely extending arms 5^a of the intermediate uprights 5, as at 15. By this arrangement, the crate may be 90 quickly and easily folded by simply pushing it laterally so as to force one of the sides of the crate downward and inward, and the other side downward and outward, the top being also forced downward, these three 95 parts of the crate being brought into parallelism with, and closely adjacent to, the bottom plate 1. In this position, the transversely extending arms 4^a of the uprights 4 fit snugly about the vertical arms 2^a of 100 the reinforcing strips 2, and the vertical arms 12^a of the end bars 12 fit snugly about the transversely extending arms 4^a of the uprights 4 of the other side of the crate, as indicated in Fig. 4 of the drawings. 105

This crate is divided into two separate compartments by means of a central partition member which is hingedly secured to the plate 1 at the longitudinal center thereof. This member comprises a frame 16 110 of suitable construction, the frame being formed preferably from sheet metal strips

which are riveted together. This frame is of a length corresponding to the width of bottom plate 1 and is hingedly secured to the bottom plate at the longitudinal center 5 thereof, by means of a plurality of suitably spaced hinges 17 secured to the bottom bar 16^a of frame 16 and to the plate 1. A similar frame 18 is hingedly secured at its lower edge to the plate 1, adjacent each end thereof, by means of suitable hinges 19 secured to the bottom plate 1 and the horizontal arm of the end reinforcing strip 2, and to the bottom bar 18^a of frame 18. The frames 18 constitute the end frames of the crate, and 10 all of the frames 16 and 18 may be revolved about their pivotal axes into a vertical position, or into a position approximately parallel with, and closely adjacent to, the bottom plate 1. In order to secure the end 15 frames and the central partition member of the crate in vertical position, I provide a spring catch 20 for each end frame, and a similar catch 21 for the center frame. The catch 20 is secured to the horizontal arm of 20 the rectangular end bar 12 of the top of the frame and extends downward into such a position as to engage in back of the top bar of frame 18, when the frame is raised. The vertical arm of this catch extends through 25 the horizontal arm of the end bar and is provided with an integral head 22 which enables the catch to be raised into inoperative position thus permitting the end frame to be folded downward about its pivotal 30 axis. The catch 21 for the center frame 16 is secured to the horizontal arm of the center bar 11 of the crate top and is extended through this bar being provided at its upper end with an integral head 23.

40 To permit folding of the crate by rotating one of the sides inward and downward, and the other side downward and outward, laterally, one end of the vertical arm 2^a of the rectangular reinforcing end strip 2 is 45 rounded upward and inward as at 2^b, the other end of this strip being of rectangular shape as at 2^c. The upper ends of the transversely extending arms 4^a of the end uprights 4 of the side frames, and the transversely extending arms 5^a of the intermediate uprights or standards 5, are also rounded 50 for a similar purpose. This permits the side frames to be rotated or folded downward transversely of the crate in one direction only, thus preventing confusion and insuring accuracy of operation.

For convenience in handling, a handle or bail 27 is pivotally secured to each of the end frames 18 so as to normally hang downward in a vertical position. These bails oc-

cupy a position closely adjacent the end frame 18 so that, when one of the frames 18 is folded inward, and the center frame 16 is folded downward over the same, these two frames are both below the upper edge of 65 the vertical arms of the rectangular reinforcing strips 2, and the other end frame 18 when folded downward is also below the upper edge of the vertical arms of the reinforcing end strips. By this arrangement, 70 when the crate is folded, the center and end frames are positioned within the crate and do not in any way increase the space occupied by the crate when in folded position.

The top, side, and end frames, and the intermediate frame or partition member, of the crate are covered with a suitable netting or wire, in the usual manner. This wire may be secured to the uprights and the strips of the various frames in any suitable manner and serves to provide an inclosing netting or fabric which prevents the escape of animals or poultry from the crate. When not in use this crate may be quickly and easily folded in the manner previously 85 described and, in this condition, may be stored in a very small space.

What I claim is:

In crates, the combination of a bottom plate, a rectangular reinforcing strip secured to the bottom plate at each end thereof, a central transversely extending strip secured to the bottom plate and provided, at each end, with a vertically extending tab, a side frame composed of rectangular uprights pivotally secured at their lower ends to a vertical arm of the rectangular reinforcing end strips and the said tabs, end strips riveted to the said uprights, a top frame composed of rectangular end bars and an intermediate rectangular bar pivotally secured at their ends to the upper ends of the transversely extending bars of the uprights of the side frames and reinforcing strips riveted thereto, end frames hingedly secured at their lower edges to the bottom plate adjacent each end thereof, an intermediate frame hingedly secured at its lower edge to the bottom plate at the longitudinal center thereof, and spring catches carried by the end and intermediate bars of the top frame adapted to engage the said end and intermediate frames so as to releasably secure the same in operative position.

In testimony whereof I affix my signature 115 in presence of two witnesses.

LAURA M. FLEMING.
